S. H. SORRELL,
SHAKER GRATE,
APPLICATION FILED APR. 13, 1921.

1,421,598.

Patented July 4, 1922.

UNITED STATES PATENT OFFICE.

SAMUEL H. SORRELL, OF ASHLAND, ALABAMA.

SHAKER GRATE.

1,421,598.

Specification of Letters Patent.

Patented July 4, 1922.

Application filed April 13, 1921. Serial No. 460,917.

To all whom it may concern:

Be it known that I, SAMUEL H. SORRELL, a citizen of the United States, residing at Ashland, in the county of Clay and State of 5 Alabama, have invented a new and useful Shaker Grate, of which the following is a specification.

This invention aims to provide novel means whereby a shaking operation may be 10 carried out in a fire-place grate.

It is within the province of the disclosure to improve generally and to enhance the utility of devices of that type to which the invention appertains.

15 With the above and other objects in view, which will appear as the description proceeds, the invention resides in the combination and arrangement of parts and in the details of construction hereinafter described 20 and claimed, it being understood that, within the scope of what is claimed, changes in the precise embodiment of the invention shown can be made without departing from the spirit of the invention.

25 In the drawing:—

Figure 1 shows in front elevation, a device constructed in accordance with the invention; Figure 2 is a top plan; Figure 3 is an end elevation; Figure 4 is a rear elevation wherein remote parts are omitted; Figure 5 is a bottom plan; Figure 6 is a section on the line 6—6 of Figure 1.

In carrying out the invention, there is provided a frame including a front post 1 35 and a front post 2, the post 2 extending downwardly a greater distance than does the post 1. The posts 1 and 2 are supplied with rearwardly extended hooks 3, whereby the frame may be held in a fire-place. The 40 posts 1 and 2 are connected by front bars 4 and 5, the lower of the said bars being denoted by the numeral 5. A back piece 6 is provided. Right-angled grate bars 7 connect the front bar 5 with the back piece 45 6. For a purpose to be explained herein- 45 after, the back piece 6 is cut away on its forward surface to form recesses 8. At one end, the back piece 6 is supplied with a depending fixed bearing 9. On the other end 50 of the back piece 6 is mounted a removable bearing 10, secured to the back piece as indicated at 11.

The reduced ends 12 of a rock shaft 14 are mounted in the bearing 10 and 9. The 55 rock shaft 14 carries forwardly extended fingers 15 located between the horizontal

portions of the grate bars 7. At their rear ends, the fingers 15 are cut away as shown at 16, to clear the lower portion of the back piece 6, the upper rear portions 17 of the 60 fingers 15 being adapted to be received in the recesses 8 of the back piece 6. The construction last above described permits the fingers 15 to have an increased amount of up and down vertical swinging movement. At 65 one end, the rock shaft 14 carries a depending crank arm 18. A forwardly extended link 19 is pivoted at 20 to the crank arm and is mounted for reciprocation in an opening 21 formed in the post 2 near to the lower end 70 thereof. The post 2 has a forwardly extended ear 22, whereon the lower end of a lever 23 is fulcrumed as shown at 24. The forward end of the link 19 is pivoted at 25 to the lever 23. 75

In practical operation, the fingers 15 on the rock shaft 14 are disposed horizontally, between the horizontal portions of the grate bars 7. Owing to this construction, the spaces between the horizontal portions of 80 the grate bars 7 are closed to some extent and, consequently, a relatively fine coal or other fuel may be used. The fingers 15 tend to prevent fine particles of fuel from falling between the grate bars 7. It is possible, however, to impart rocking movement to the shaft 14, by way of the link 19 and the lever 23. Under such circumstances, the fingers 15 on the rock shaft 14 will swing upwardly and downwardly be- 85 tween the grate bars 7 and permit a shaking of the device. The construction is such that a clean, bright fire may be maintained at all times, without poker work and, it is to be noted, the fine particles of fuel will be 90 held back and burned, only the finely di- 95 vided portions of the ashes passing between the fingers 15 and the horizontal portions of the grate bars 7.

Having thus described the invention, what 100 is claimed is:—

1. In a device of the class described, a frame embodying front posts, a front bar connecting the posts, a back piece, and grate bars connecting the front bar with the back 105 piece; a shaft mounted to rock on the back piece; fingers carried by the shaft and located between the grate bars; a lever mounted to swing on one post; and a link forming a connection between the lever and the shaft, 110 the said post having an opening for the reception of the link.

2. In a device of the class described, a frame including grate bars; a shaft mounted to rock on the rear portion of the frame and provided with fingers extended between the grate bars; a crank arm on the shaft; an upwardly extended lever disposed in front of the frame and fulcrumed at its lower end on the frame; and a link forming an operative connection between the intermediate portion of the lever and the crank arm.
3. In a device of the class described, a frame comprising grate bars and a back piece connecting the grate bars, the back piece being provided in its forward surface

with a recess; a shaft mounted to rock on the back piece; fingers carried by the shaft and cooperating with the back piece, the fingers being cut away to clear the back piece and being extended into the recess; and means for rocking the shaft.

In testimony that I claim the foregoing as my own, I have hereto affixed my signature in the presence of two witnesses.

SAMUEL H. SORRELL.
